GLOVE BOX DOOR FOR THE DASHBOARD GLOVE BOX OF A VEHICLE

William C. Rieske, 17711 Wormer, Detroit, Mich.

Filed Oct. 18, 1962, Ser. No. 72,176

Term of patent 14 years

(Cl. D14—6)

FIGURE 1 is a front perspective view of a glove box door for the dashboard glove box of a vehicle embodying my new design;

FIGURE 2 is a rear perspective view of the glove box door of the dashboard glove box of a vehicle of FIGURE 1; and

FIGURE 3 is a sectional view taken substantially along the line 3—3 of FIGURE 2 looking in the direction of the arrows.

Portions are shown broken away to indicate indeterminate length.

I claim:

The ornamental design for a glove box door for the dashboard glove box of a vehicle, substantially as shown and described.
